UNITED STATES PATENT OFFICE

1,975,935

DUSTER

John Glover, Chicago, Ill., assignor to Midway Chemical Company, Chicago, Ill., a corporation of Delaware

Application April 20, 1931, Serial No. 531,293

3 Claims. (Cl. 15—229)

The present invention relates to a duster and has to do particularly with the formation of a metallic support or back therefor.

At the present time, there are many so-called dusters or dry mops having suitable thrums, either treated or untreated to absorb dust.

The preferred forms of these devices are those which are adapted to be used upon a floor and held by a handle. Such type of duster has heretofore in the past generally been made of wood.

The wooden back or support therefor has assumed a number of different configurations. Metal backed dusters have not been highly popular because of the expense of production, with consequent high retail price, such expense being either due to the multiplicity of parts, expensive assembly, or the waste of material.

The object of the present invention is to provide a new and improved metal back for a duster.

A further object of the invention is to provide a new and improved form of duster.

A still further object of the invention is to provide a blank of unique design particularly adapted to be used for forming the back of a duster or the like.

Another object of the invention is a new and simplified structure for a duster or the like.

These objects, and such other objects as may hereinafter appear, are obtained by the novel construction, unique arrangement, and improved combination of elements illustrated in the accompanying drawing, showing one embodiment of the invention, and in which:

Figure 1 is a plan view of the blank used in producing a duster support or back hereinafter to be described;

Figure 2 is a plan view of the top of a duster made from the blank shown in Figure 1;

Figure 3 is a front view of the device shown in Figure 2; and

Figure 4 is a transverse section on the line 4—4 of Figure 2.

Like reference characters are used to designate similar parts in the drawing and in the description of the invention which follows.

Reference will be had first to Figure 1. The blank there shown includes a body comprising sections 10 and 11 divided one from the other by a plurality of dotted lines 12, 13 and 14, which dotted lines are adapted to represent folds later to be made in the blank. Sections 10 and 11 form a horizontal crown sheet in the completed mop head. Around the section 10 and 55 also around the section 11 are complementally

arranged tabs which are designated 15, 16, 17, 18, 19, 20, 21, 22, 23 and 24. Said tabs or extensions have apertures 25 therein to receive rivets for securing a strip of thrums 26 to the duster head, said thrums 26 being held together by a fabric strip 27 in which there are stitches 28.

From the blank shown in Figure 1, the device illustrated in Figure 2 is adapted to be manufactured. By folding the blank on the lines 12, 13 and 14, a well or groove which is separated from the blanks 10 and 11 by the folds 12 and 14 is obtained. Between the sections 10 and 11, 12 and 14 space for the insertion of a socket is thus obtained.

The depth of the trench or groove defined by the folds 12, 13 and 14 is a matter of choice, and the folds 12 and 14 are generally arranged to be slightly further apart at the rear of the duster head to leave room for the front end 29 of a socket 30 to which socket a handle, not shown, is adapted to be secured in any conventional manner.

The strip of thrums 26 is adapted to be riveted or otherwise secured through the strip thereof which is secured to the flanges 15, 16, 17, 18, 19, 20, 21, 22, 23, and 24, after said flanges are folded until normal to the top face of the sections 10 and 11, as is shown in Figure 3.

Thus a relatively simple blank is provided for the production of duster heads, and instead of wasting a large amount of material to provide by direct cutting, a blank following the outline of the device shown in Figure 2, a more economical blank is provided, as is shown in Figure 1, the fold of the blank shown in said Figure 1 being a relatively simple and inexpensive operation. Such arrangement concurrently provides simplified means for securing the socket 30 upon the device by means of the bolt or machine screw 31 extension through the vertical walls of the trench between sections 10 and 11.

I claim:

1. In combination, a mop having thrums, a handle, and a mop head comprising a single sheet of metal long in transverse dimension and short in its front to back dimension, portions of the outer edges of said sheet of metal being turned down to form a rim to receive the thrums, and the central part of said sheet being sharply depressed to form a front to back handle receiving groove deep at the back of the head and sloping upwardly to the top level of said head at the front thereof, said handle receiving groove supporting the end of said handle between its opposed walls.

2. In combination, a mop having thrums, a

handle, a socket for said handle having a flattened perforated end for pivotal fastening, a mop head comprising a single sheet of metal long in the transverse dimension and short in its front to back dimension, portions of the outer edges of said sheet being perforated and bent downwardly at an angle to the top of said sheet for receiving and holding said thrums, said sheet having a groove midway of the transverse dimension of said sheet, said groove being sufficiently wide to receive the flattened perforated end of said socket and extending substantially the entire distance from the front to the back of said sheet, the groove being deep at the back edge of said head and the bottom thereof sloping upwardly in a straight line to the level of the top of said head at the front thereof, the walls of said groove being perforated adjacent the deepest part thereof, and a pin extending through the perforated end of said socket and the perforations in the walls of the groove when the flattened portion of said socket is in said groove to hold said flattened perforated portion pivotally within said groove, the back edge of said head being shorter than the front edge thereof by an amount equal to the

width of material included in the walls and bottom of said groove at said back edge.

3. A mop head formed from a single sheet metal blank, said sheet having two substantially flat divergent arms each having the edge portions thereof bend downwards at an angle of ninety degrees and perforated at selected positions, there being a depressed portion between said arms to form a groove therebetween substantially at right angles thereto, said groove being deep and relatively wide at one end and becoming shallow and narrower towards the other end, said latter mentioned end merging into the flat faces of said arms near the side opposite said deep portion of said groove, the walls of said groove having opposed perforations therein near the deep end thereof, said groove being formed by folding the material of the blank on lines diverging from a point near the side opposite said deep portion of said groove, the back edge of said head being shorter than the front edge thereof by a distance equal to the distance between the outer lines of folding on said back edge.

JOHN GLOVER.
